UNITED STATES PATENT OFFICE

2,465,082

ELECTRONIC AMPLIFIER FOR GALVANOMETER OSCILLOGRAPHS

Kenneth R. Geiser, Schenectady, N. Y., assignor
to General Electric Company, a corporation of
New York

Application August 2, 1944, Serial No. 547,794

2 Claims. (Cl. 171—95)

1

My invention relates primarily to a novel method of energizing galvanometers of the oscillograph type, and to amplifier arrangements therefor which enable the use of the oscillograph type of galvanometer to be extended to the measurement and study of rapidly varying feeble phenomena with much less amplifier equipment than has heretofore been considered necessary. In carrying my invention into effect, I energize the galvanometer by unidirectional current pulsations of a frequency well above the natural frequency of vibration of its moving element, and vary the magnitude of the current pulsations in response to the phenomena to be investigated. Such magnitude variation may be faithfully reproduced up to frequencies usually employed with oscillograph galvanometers.

The features of my invention which are believed to be novel and patentable will be pointed out in the claims appended hereto. For a better understanding of my invention, reference is made in the following description to the accompanying drawings in which Fig. 1 represents portions of an oscillograph galvanometer of the type used in my invention; Fig. 2 represents the deflection-frequency characteristics of an oscillograph galvanometer energized by alternating current; Fig. 3 indicates an oscillograph galvanometer energized from an A.-C. source through a half-wave rectifier; Fig. 4 represents the deflection-frequency response of an oscillograph galvanometer when energized by unidirectional current pulsations; Fig. 5 represents a pulsating unidirectional current curve and the corresponding response curve of an oscillograph galvanometer when used in accordance with my method; Figs. 6, 10 and 12 show different ways of amplifying feeble measurement currents for recording with an oscillograph type galvanometer in accordance with my invention using a gas-filled tube amplifier; Figs. 7, 8 and 9 will be referred to in explaining how the tube output current of Fig. 6 varies in response to changes in phase relation between the plate and grid voltages; Fig. 11 will be referred to in explaining the operation of Fig. 10; Fig. 13 represents a high frequency voltage measuring scheme using an oscillograph galvanometer and full-wave rectifier; Fig. 14 represents the use of a high vacuum tube in a system embodying my invention; and Fig. 15 are explanatory curves of the operation of Fig. 14.

The usual Duddell type oscillograph galvanometer consists of means for producing a strong unidirectional magnetic field between pole pieces 1 and 2, Fig. 1. In this field and at right angles thereto, is supported a bifilar type conductor suspension 3 which is the equivalent of a coil having one turn and consists of a fine conductor wire looped over a pulley 4 and secured at 5, and stretched taut by a lever 6 and spring 7. The

pair of wires are held parallel in the field between bridges 8 and 9 and the plane of the wires is normally parallel to the direction of the field in which located. The current to be measured or investigated is sent through the loop, causing a motor action which causes the plane of the two wires to turn in a direction dependent on the current direction and by an amount proportional to the current strength. This motion is traced or recorded by a light beam photographic method by utilizing a tiny mirror 10 which is fastened to the two wires between the bridges. When the current is removed, the tension of the wires returns the mirror to zero position. The moving element is contained in an oil-filled damping cell having a transparent window 11 therein to accommodate the light beam. Reference is made to United States Patent 1,800,018 for a more detailed description of such galvanometers. The Duddell galvanometer is essentially a current sensitive instrument having low resistance and a high natural period of torsional oscillation. Practicable galvanometers of this type require a peak current of the order of 130 milliamperes for full deflection and are capable of following current variations or reversals up to about 2500 cycles per second.

There are many minute vibratory measurements which cannot be directly converted into a sufficient current change to afford a satisfactory measurement deflection of this type of galvanometer. One example of this are measurements taken with wire resistance type strain gauges of the type described in United States Letters Patent No. 2,292,549 to Simmons. Where such measurements are to be recorded with the galvanometer type oscillograph, it becomes necessary to employ amplifier apparatus between the measurement circuit and the oscillograph and heretofore this has consisted of at least one stage of voltage amplification and a power stage employing a tube capable of supplying the high current necessary for good galvanometer deflections.

An important object of my invention is to reduce the amplifier equipment necessary for such measurements and in accomplishing this result, I energize the galvanometer with unidirectional current pulsations of a frequency higher than its natural period of vibration and modulate this high frequency supply in accordance with the desired measurements.

The vibration characteristics of the oscillograph type galvanometer when energized by constant voltage alternating current are represented in Fig. 2. If the galvanometer of Fig. 1 be energized by a constant voltage alternating current and we vary the frequency from zero up to 10,000 cycles per second, the amplitude of vibration of the galvanometer may be represented by the

curves of Fig. 2. With the usual damping the deflection amplitude of the galvanometer will remain constant and follow the oscillations of the alternating current up to about 3000 cycles per second. At higher frequencies the amplitude drops off as shown by the full lines and becomes practically zero at about 6000 cycles per second. If the galvanometer were undamped as by removing the damping oil from the cell, the amplitude of oscillations would increase in the vicinity of the natural undamped period of vibration of the suspension as represented by the dotted line curves of Fig. 2. The resonant frequency occurs at about 4000 cycles per second, and again the oscillation amplitude becomes practically zero at about 6000 cycles per second.

If, now, I place a rectifier in the galvanometer circuit as represented in Fig. 3 and repeat the test with the galvanometer damped, I have discovered that I can obtain the deflection amplitude response represented in Fig. 4. It is noted that the deflection is only on one side of zero due to the fact that the galvanometer is following a rectified current wave. The galvanometer follows the half-wave current pulsations to about 3000 pulsations per second, and for higher frequencies, drops off and becomes substantially constant between 6000 and 7000 cycles per second and does not drop to zero as in Fig. 2. This is due to the fact that the unidirectional current flowing through the galvanometer tends to deflect it to only one side of zero, and this force is balanced by the restoring tension of the suspension so that the galvanometer will assume a balanced position corresponding to the mean value of the unidirectional current. It is to be understood that above 7000 cycles the galvanometer does not follow the current pulsations as it does below 4000 cycles but assumes a means deflection where the mean deflecting force and the restoring force are balanced. The transition between these galvanometer characteristics occurs between the two frequencies last mentioned. In producing the full curve of Fig. 4, the maximum value of the unidirectional current pulsations of variable frequency was held constant. If, now, the value of these current pulsations be increased or decreased, the deflection obtained at any frequency will rise and fall accordingly. Hence it is seen that below about 3000 cycles the oscilloscope may be used in the usual way for either direct or alternating current measurements, and the magnitude of its deflection will be independent of frequency variations and proportional to current magnitude. Also above 7000 cycles per second the galvanometer may be used to measure the mean value of direct current pulsations and its deflection will be practically independent of frequency variations. Below 3000 cycles the galvanometer may be used to study fundamental wave form, but above 7000 cycles the galvanometer will not follow the carrier wave, and the wave form of the carrier wave does not influence the deflection except as it may vary the mean value of the current. It will, however, follow the lower frequency modulating wave.

So far as I am aware, the characteristics of the galvanometer type oscilloscope when energized by unidirectional current pulsations having a frequency above the natural period of vibration of the galvanometer have never before been investigated or utilized for any purpose. Hence, I have discovered a new method of using this type of oscilloscope which does not interfere with its uses as heretofore employed, and which may

be exemplified by the curves of Fig. 5 representing, in curve 12, pulsating direct current of variable wave form and frequency of 7000 cycles per second or above, and curve 13 the corresponding mean value of the current. The oscilloscope type galvanometer may be used to produce the curve 13 notwithstanding the fact that the frequency is above the natural period of oscillation of the galvanometer and still farther above the normal frequency measurement range of the galvanometer. Moreover, the discovery enables me to use the galvanometer type oscilloscope for measurements of feeble currents with a reduced amount of amplifier equipment even though the measurement current be direct or alternating and within the ordinary frequency measurement range of such galvanometers as will now be explained.

In Fig. 6, I have shown a transformer 14 supplied from a source of alternating current of pulsating direct current 15 having a frequency of the order of 10,000 cycles per second. A thermionic tube 16 of the tiny, gas-filled type has its cathode 17 connected to the midpoint of the 20 transformer secondary, its grid 18 connected to one end of the transformer secondary through a condenser 19, and its plate 20 connected to the other end of the transformer secondary through the oscilloscope galvanometer 3. The grid and 25 plate are also connected through a variable resistance 21 which may be a wire resistance strain gauge of the type described in Patent No. 2,292,549.

It is evident that only direct current pulsations 30 of a frequency of 10,000 cycles per second will flow in the plate-galvanometer circuit and hence are within the range of the galvanometer response which has been explained above, and because of the use of a tube capable of passing considerable current, ample current can be made to flow through the galvanometer to give good response. There are a variety of ways to cause the current flow in the plate-galvanometer circuit to be proportional to a desired measurement. In 35 Fig. 6 this is done by varying the phase relation between the grid and anode voltages, thus utilizing a well-known characteristic of the tube. Each shaded area of the positive current pulses in Fig. 7 represents the current flow per cycle in the 40 plate circuit of the tube when the grid voltage is nearly in phase with the anode voltage, and in Fig. 8 the shaded area represents such current flow when the grid voltage is appreciably out of phase with the anode voltage. Fig. 9 represents 45 the average plate circuit current flow as a function of phase angle between grid and plate voltages where zero current flow corresponds to the maximum phase angle ϕ between grid and plate voltages at which current flow occurs. The average current can be found from the expression

$$I = I_{\text{crest}} \frac{(1 + \cos \phi)}{\pi}$$

Referring again to Fig. 6, it is apparent that as 50 resistance 21 is varied, the phase angle between plate and grid voltages will vary, and therefore the average plate current will change such that, by calibration, the average current through the galvanometer and its deflection may represent an 55 amplified change in the resistance 21 corresponding to the change in strain or other factor which causes such resistance change. Instead of varying the resistance 21, I might vary the condenser 19 to obtain the desired results.

Fig. 10 is similar to Fig. 6 except that the con-

denser is replaced by an inductance 22 and here again either the inductance or the resistance 21 may be varied to control the amplified output current of the tube 16. Fig. 11 represents the vector relations between the anode and grid voltages for Fig. 10. As the resistance 21 is changed, its current 21*i* is changed, and the current 22*i* of the inductance is changed, varying the phase between the plate and grid voltages as indicated.

Fig. 12 represents another method in which a bridge circuit may be used to control the phase angle between the plate and grid voltages of a gas-filled amplifier tube 16. Here the grid voltage is taken off of a bridge circuit through a transformer 23 and compared to the plate voltage by the connection 24. The bridge contains three resistance arms, one, 21, of which is variable and may be a wire strain gauge. The other arm 25 is an inductance. The bridge is connected across the high frequency source of supply for the tube such that variations in the resistance 21 will cause the desired phase shift in the voltage across the bridge and vary the output of the tube accordingly. In Figs. 6, 10, and 12, the variable may oscillate up to 2500 cycles per second and be faithfully recorded by the oscillograph.

The new method of using the oscillograph galvanometer as herein described may be used to measure the mean value of any alternating current voltage having a frequency above about 3500 cycles by energizing such galvanometer from the frequency source through a full-wave rectifier as represented in Fig. 13. This may be useful to record rapid fluctuations in the mean value of the alternating current voltages and currents. It is to be observed here that with full-wave rectification the rectified pulsations will be at double the frequency of the alternating current source.

In Figs. 6, 10, and 12 a gas-filled type of amplifier tube was employed, since the plate current of such a tube is sufficient to operate the oscillograph type of galvanometer directly. In Fig. 14, I have represented a modification of my invention employing an amplifier tube 26 of the high vacuum type having a plate current output limited to the order of about 10 milliamperes. To obtain sufficient output current to operate the galvanometer, the plate current of the tube is stepped up by a current transformer 27. The circuit is controlled in the same way as in Fig. 6 as by varying the resistance 21. However, the characteristics of this form of tube are as represented in Fig. 15.

In the upper left portion of Fig. 15 are found the transfer characteristics at various plate voltages E_p . In the lower left portion of Fig. 15 is shown at E_g a sine wave of voltage applied to the grid; and also the sine wave of applied plate voltage E_{p_0} , $E_{p_{30}}$, etc., hold constant at 200 volts but at different phase relations with respect to the grid voltage, E_{p_0} meaning a 0-degree phase angle, $E_{p_{30}}$ a 30-degree phase angle, etc. The zero line of grid voltage wave E_g is positioned at any point of the grid voltage scale of the transfer characteristics by choosing the proper amount of bias voltage determined by the bias of battery 28 in Fig. 14. At the upper right in Fig. 15 is shown the plate current I_p for different phase angles of grid and plate voltages for a plate voltage of 200 volts. It is seen that the plate current I_{p_0} is a maximum when the plate and grid voltages are in phase and decreases as this phase angle increases, the plate currents for 0, 30, 60, 90, and

120 degrees phase angle being represented in decreasing magnitude.

The output of tube 26, Fig. 14, will then comprise direct current pulsations of a frequency of, say, 8000 per second of varying magnitude, the magnitude being determined by the phase angle between plate and grid voltages. While the output current is not sufficient to obtain good response of the galvanometer 3, it can be stepped up by the required current transformer at 27 so that it is sufficient. The current transformer secondary output is rectified and influences the oscillograph galvanometer as explained in connection with Fig. 5.

In accordance with the provisions of the patent statutes I have described the principle of operation of my invention, together with the apparatus which I now consider to represent the best embodiment thereof, but I desire to have it understood that the apparatus shown is only illustrative and that the invention may be carried out by other means.

What I claim as new and desire to secure by Letters Patent of the United States is:

1. The method of measuring wave form phenomena with an oscillograph type galvanometer such that at least complete half cycles of the wave may be visualized, such wave form phenomena varying at a frequency within the range of 25 to 4000 cycles per second and which is well below the natural period of vibration of the galvanometer, which consists in energizing said galvanometer with direct current pulsations of a constant frequency which is at least 7000 cycles per second and well above the natural period of vibration of the galvanometer, and superimposing on such energizing current the wave to be measured by amplifying such pulsations solely in direct proportion to such wave.

2. The method of tracing the wave form of varying current phenomena having a frequency between 25 and 4000 cycles per second with an oscillograph type galvanometer so that at least complete half cycles of the wave may be visualized and where such varying current is too weak to produce a good response of the galvanometer, which consists in energizing the galvanometer with direct current pulsations of good galvanometer response magnitude but at a frequency of at least 7000 cycles per second and which is well above the natural period of vibration of the galvanometer, and directly modulating the value of such pulsating energizing current by amplification solely in response to the varying current phenomena to be traced.

KENNETH R. GEISER.
